UNITED STATES PATENT OFFICE

1,973,577

RADIATOR

John N. Murphy, Springfield, Ill., assignor of one-half to August F. Maurer, Springfield, Ill.

Application August 29, 1932, Serial No. 630,869

12 Claims. (Cl. 257—151)

This invention relates to radiators, and particularly to an improved construction of a section thereof.

The present invention is particularly well adapted for use in radiator sections comprising a plurality of connected tubular portions, and is intended primarily for use in the end section of a radiator.

One object of the present invention is to provide a radiator section of novel construction which may be readily adapted for use in various types of heating systems as, for example, one or two pipe steam, hot water or vapor systems.

Another object of the invention is to provide a construction of radiator section which will insure the ready removal of air from the entire radiator, including the upper and lower portions thereof, thereby providing for quicker and more uniform heating of the radiator.

20 A further object of the invention is to provide a radiator section embodying a structure whereby the section may be adapted to numerous types of heating systems, thereby permitting a single pattern to serve in the construction of radiator sections for use in different systems, and avoiding the necessity of providing different patterns for sections used in the various systems.

A still further object of the invention is to improve devices of the character described in sundry details hereinafter referred to, and particularly pointed out in the appended claims.

One embodiment of the present invention is shown, for illustrative purposes, in the accompanying drawings, in which

35 Fig. 1 is a side elevational view of a radiator section embodying features of the present invention;

Fig. 2 is a vertical longitudinal sectional elevation of the structure illustrated in Fig. 1, and 40 taken substantially as indicated by the line 2—2 thereof;

Fig. 3 is a side elevational view of a radiator comprising a plurality of sections, the end one of which has a portion thereof broken away to illustrate the application of the present invention thereto;

Fig. 4 is an elevational view of an ordinary automatic air valve which may be employed under certain conditions in conjunction with my improved radiator structure; and

55 Figs. 5, 6, 7 and 8 are fragmentary sectional elevational views of the upper portion of a radiator section embodying my improved construction and illustrating the manner of its use in various types of heating systems.

Referring particularly to Figs. 1 to 4, inclusive, of the drawings, the illustrative embodiment of the present invention is shown in conjunction with a radiator section comprising a plurality of vertically disposed substantially parallel tubular portions 1a, 1b and 1c adapted to communicate with each other adjacent their upper and lower ends, it being understood that the invention may be employed in conjunction with radiators of various other constructions.

Positioned preferably adjacent the upper end of the central or intermediate tubular portion 1b of the type of radiator shown is a horizontal partition 2 extending across the interior of the tubular portion and providing lower and upper chambers 5 and 10, respectively, within the section, the partition 2 having an upwardly extending lug 11 formed integrally therewith and extending partially across the interior of the tubular portion within the chamber 10. The horizontally disposed partition is provided with a passage extending therethrough comprising, in the present instance, a vertically disposed port 3 and a transversely or horizontally disposed aperture 18 formed in the lug 11 and extending outwardly 80 to the exterior of the radiator section.

Formed also in the radiator section 1 are a plurality of openings 12, 13, 14 and 15 which may be screw-threaded for the reception of connecting nipples for connecting adjacent sections in the usual manner, and by which communication between adjacent sections may be established, or if the improved section is employed as an end section of a radiator unit, a plug 17 may be positioned in the opening 12 as illustrated in Figs. 1 and 2, and if the section is employed in a one-pipe system, the opening 14 may be closed by a plug or closure 16 as illustrated in Fig. 1.

Formed also in the body of the section and communicating with the chamber 10 is an aperture 6 into which a plug 7 may be screw-threaded, and below the partition 2 is formed an aperture 9 communicating with the chamber 5 and adapted to receive a screw-threaded plug 8.

Screw-threaded into the aperture 18 formed in 100 and extending through the lug 11 is a plug 4, preferably of greater length than the plugs 7 and 8, it being understood that the apertures 6, 18 and 9 are preferably of substantially uniform size or diameter so that, if desired, the plugs 7, 4 105 and 8 may be interchangeably positioned in the respective apertures for adapting the improved section to various types of heating systems as illustrated in Figs. 5 to 8, inclusive.

Referring to Figs. 5, 6, 7 and 8, Fig. 5 illustrates 110

the use of my improved radiator section in a one or two-pipe steam or vapor system after the manner of an ordinary unimproved section with the plug 4 of Fig. 2 having been replaced by the plug 7, and an automatic air valve 19 of well known construction positioned in the aperture 6 from which the plug 7 has been removed from the position shown in Fig. 2, thereby providing communication between the chambers 5 and 10 and permitting the circulation of steam or vapor in the usual way.

It has been found, however, that in such an arrangement, steam frequently passes quickly through the upper portion of the radiator and, 15 in the usual manner, acts to close the air valve 19 before all of the air has been expelled from the central portions of the radiator, thereby retarding the passage of steam into certain of the sections and causing the center to be air bound 20 and retard heating of the radiator.

To overcome this condition, particularly in a one-pipe steam or vapor system, the long plug 4, as shown in Fig. 6, is positioned in the aperture 18 in a manner to close the passage through 25 the partition 2 and prevent communication between the upper end of the chamber 5 and the chamber 19. In such a case, the plug 7 may be replaced in the aperture 6 and the air valve 19 positioned in the aperture 9 communicating with 30 the chamber 5. With the arrangement shown in Fig. 6, any steam passing quickly through the upper portion of the radiator unit is required to pass downwardly, in the type of radiator section shown in Fig. 1, through the tubular portions 35 1a and 1c, through the lower end of the radiator and thence upwardly through the central or intermediate tubular portion 1b before reaching the air valve, thereby permitting the air from the lower central portion of the 40 radiator unit to be discharged through the air valve before it is closed by the action of the steam. It will be observed that by such an arrangement, the air is completely discharged 45 from the entire radiator unit before the steam acts to close the valve.

The arrangement shown in Fig. 7 is particularly well adapted for two-pipe steam or vapor systems where a trap is used and no air valve is needed, the plugs 4 and 7 having been reversed 50 from the arrangement shown in Fig. 6 so that a free passage is established for the heating fluid between the chambers 5 and 10, the valve 19 of Fig. 6 having been replaced by the plug 8 in the aperture 9.

Fig. 8 illustrates an arrangement for use in either a one or two-pipe water system, the position of the plugs 7 and 8 remaining the same as in Fig. 7, but the long plug 4 having been replaced by a manually operated air valve 20 in the aperture 6 for removing trapped air from the upper part of the radiator unit.

It will be observed from the foregoing description and by reference to Fig. 7, that if desired, or in an emergency, my improved radiator section, 65 with the plugs 4, 7 and 8 positioned as shown in Fig. 7, may be used as an intermediate section of a radiator unit merely by removing the plug 17 from the opening 12 and connecting up the improved section with adjacent sections by the 70 use of nipples in the well known manner and as above described.

It will be observed also from the foregoing description that the present invention provides a novel construction and arrangement of a radiator section which may be readily adapted for use

in various types of heating systems, and wherein by proper arrangement, the removal of air from the entire radiator unit including the upper and lower portions thereof may be accomplished, thereby providing quicker and more uniform 80 heating of the radiator.

Obviously, the present invention is not limited to the precise construction and arrangement shown and described as the same may be variously modified. Moreover, all the features of the invention need not be used conjointly as the same may be used to advantage in variously different combinations and sub-combinations.

Having thus described my invention, what I claim as new and desire to cover by Letters 90 Patent is:—

1. A heat exchange device comprising a hollow radiator section, a transverse partition in said section forming upper and lower chambers therein, said section having openings formed 95 therein communicating respectively with said chambers and with adjacent sections, and having apertures communicating respectively with said upper and lower chambers.

2. A heat exchange device comprising a hollow radiator section, a substantially transverse partition in said section forming upper and lower chambers therein, said partition having a passage therethrough, means for closing said passage, said section having openings formed therein for communication with adjacent sections, and having an aperture communicating with said lower chamber.

3. A heat exchange device comprising a hollow radiator section, a substantially transverse partition in said section forming upper and lower chambers therein, said partition having a passage therethrough, means extending outside the section for closing said passage, said section having openings formed therein for communication 115 with adjacent sections, and having a threaded aperture communicating with said lower chamber.

4. A heat exchange device comprising a hollow radiator section having openings formed 120 therein for providing communication with adjacent sections, a substantially transverse partition having a passage formed therein positioned in said section and forming upper and lower chambers therein, manually actuated means for 125 closing said passage, said section having threaded apertures formed therein and communicating with the respective chambers formed in the section, and means for closing said apertures.

5. A hollow radiator section having openings 130 formed therein for providing communication with adjacent sections and comprising a plurality of communicating hollow tubular portions, a partition having a passage formed therein positioned in one of said tubular portions and forming upper and lower chambers in said radiator section, said section having a plurality of apertures formed therein communicating with the respective chambers, one of said apertures extending through a portion of said partition and 140 forming a part of the passage therein.

6. A hollow radiator section having openings 145 formed therein for providing communication with adjacent sections and comprising a plurality of communicating substantially parallel hollow tubular portions, a partition having a passage formed therein positioned in an intermediate tubular portion and forming upper and lower chambers in said radiator section, said section having a plurality of screw-threaded 150

- apertures of substantially uniform size formed therein communicating respectively with said upper chamber and said intermediate tubular portion, one of said apertures extending through 5 a portion of said partition and forming part of the passage therein.
7. A hollow radiator section having openings formed therein for providing communication with adjacent sections and comprising a plurality of 10 communicating substantially parallel hollow tubular portions, a partition having a passage extending therethrough positioned in an intermediate tubular portion and forming communicating upper and lower chambers in said radiator section, said section having a plurality of screw-threaded apertures of substantially uniform size formed therein communicating respectively with said upper chamber and said intermediate tubular portion, one of said apertures extending 15 through a portion of said partition and into said upper chamber and forming a part of the passage extending through the partition.
8. In a radiator section comprising a plurality of communicating tubular portions and having a plurality of openings formed in the section for providing communication with adjacent sections, the combination of a partition having a passage formed therein positioned in one of said tubular portions and forming upper and lower 20 communicating chambers in the radiator section, said section having a plurality of apertures formed therein communicating with said upper chamber and said lower chamber respectively, an air valve in one of said apertures, and a plug in the other of said apertures.
9. In a radiator section comprising a plurality of communicating tubular portions and having a plurality of openings formed in the section for providing communication with adjacent sections, the combination of a partition having a passage formed therein positioned in one of said tubular portions and forming upper and lower communicating chambers in the radiator section, said section having a plurality of apertures formed 25 therein communicating with said upper chamber, an air valve in one of said apertures, a plug in the other aperture, said radiator section having 30
- an aperture formed therein communicating with said lower chamber, and a plug in said last mentioned aperture.
10. In a radiator section comprising a plurality of communicating tubular portions and having a plurality of openings formed in the section for providing communication with adjacent sections, the combination of a partition having a passage formed therein positioned in one of said tubular portions and forming upper and lower communicating chambers in the radiator section, said section having a plurality of apertures formed 35 therein communicating with said upper chamber, a plug in one of said apertures, means positioned in the other aperture and adapted to close the passage formed in said partition, said radiator section having an aperture formed therein communicating with said lower chamber, and an air valve positioned in said last mentioned aperture.
11. In a radiator section comprising a plurality of communicating tubular portions and having a plurality of openings formed in the section for providing communication with adjacent sections, the combination of a partition having a passage formed therein positioned in one of said tubular portions and forming upper and lower communicating chambers in the radiator section, said section having a plurality of apertures formed 40 therein communicating respectively with said upper and lower chambers, and a plurality of plugs positioned in said apertures.
12. In a radiator section comprising a plurality of communicating tubular portions and having a plurality of openings formed in the section for providing communication with adjacent sections, the combination of a partition having a passage formed therein positioned in one of said tubular portions and forming upper and lower communicating chambers in the radiator section, said section having a plurality of apertures formed 45 therein communicating with said upper chamber, a manually controlled air valve in one of said apertures, a plug in the other aperture, said radiator section having an aperture formed therein communicating with said lower chamber, and a plug in said last mentioned aperture.
